BLANCHER

Frank D. Chapman, Berlin, Wis.

Application February 12, 1940, Serial No. 318,488

16 Claims. (Cl. 53—18)

The present invention relates in general to improvements in the art of heat treating comestibles, and relates more specifically to improvements in the construction and operation of mechanisms for blanching or otherwise heat treating foods in order to preserve the color, and to improve the palatability, and other characteristics thereof.

Generally defined, an object of this invention is to provide an improved machine for blanching or otherwise heat treating foods in an improved manner, which machine is simple and compact in construction and highly efficient in use.

It has heretofore been common commercial practice in the food treating and canning industry, to blanch legumes such as green peas, continuously and in bulk, before measured batches of the commodity were placed into the final receptacles or cans. Because of the diverse characteristics of the legumes, it is absolutely necessary in order to insure most effective blanching of all peas, to vary the duration of the treatment, the temperature applied, and the rate of heat transfer, to suit the specific characteristics of the product being treated, and it was impossible to do this with the old methods and apparatus. This would result in overtreatment of the tender peas and insufficient treatment of the harder peas with resultant inequality in the final product. In order to overcome these objections, it has recently been proposed to blanch or heat treat legumes such as green peas after measured batches thereof have been placed in the successive cans and before the receptacles are sealed, by heat treating the open topped food and liquid laden containers in the successive heating zones of an ordinary exhaust box, and by discarding the treating liquid by inversion of each can against a drainage screen after each batch is treated. While this new method of blanching has some advantages over the old bulk process, it also has many disadvantages and requires considerable tedious and costly manual labor. The new method depends largely upon human judgment and cannot be carried on in simplified automatic mechanism, and it does not provide for convenient and accurate variation in the treating time and temperature, and in the rate of heat transfer, so that desired uniformity of treatment is still impossible with the improved method.

The present invention therefore contemplates provision of a new and useful automatically functioning blancher which is operable at relatively

high speed and with minimum attention to carry on batch blanching of legumes or the like.

Another specific object of my present invention is to provide an improved blanching machine which is highly flexible in operation and which is therefore adapted to quickly and effectively meet various operating conditions best suited for treatment of the particular product being handled.

10 A further specific object of this invention is to provide an improved blancher wherein the blanching treatment can be accurately controlled and readily varied at the will of the operator, so as to vary either the duration of the treatment, the temperature, or the rate of temperature increase and decrease.

15 Still another specific object of my invention is to provide an improved blancher assemblage of relatively simple and compact construction, which will effectively cooperate with one or more relatively standard automatic receptacle filling units or the like.

20 An additional specific object of the present invention is to provide an improved blanching method and structure adapted to effectively treat diverse materials such as green peas, whole string beans, or practically any commodity, bulk batches of which may be inserted in a bucket or receptacle and subsequently delivered therefrom by dumping the bucket.

25 A further additional specific object of my invention is to provide an improved machine for heat treating relatively small successive batches of granular commodity, in which the individual batches may be heated, permitted to soak, or cooled in a manner whereby most efficient final treatment of the material is assured regardless of variations in the characteristics of the material in the several batches.

30 Another additional specific object of the invention is to provide an improved liquid measuring pocket and control valve assemblage for batch measuring and delivering machines of various types.

35 These and other specific objects and advantages of the present invention, will be apparent from the following detailed description.

40 A clear conception of the several improved features constituting my present invention, and of the mode of constructing and of utilizing an automatic batch blancher built in accordance with the improvement, may be had by referring to the drawings accompanying and forming part 45 of this specification wherein like reference char-

acters designate the same or similar parts in the various views.

Fig. 1 is a top view of one of my improved blanchers embodying eight batch treating pockets, and having some portions thereof shown diagrammatically;

Fig. 2 is a part sectional side view of the blanching machine of Fig. 1;

Fig. 3 is a fragment of a development of part of the blancher shown in Figs. 1 and 2;

Fig. 4 is an enlarged central vertical section through one of the improved liquid batch measuring units, showing the measuring piston just arriving at its lowermost position;

Fig. 5 is a similar enlarged section through the liquid measuring unit, and showing the displacement piston just arriving at its uppermost position;

Fig. 6 is a fragmentary similar enlargement of the liquid measuring unit, showing the control valve in neutral or locking position;

Fig. 7 is a further enlarged outside view of the rotary control valve for the liquid measuring unit;

Fig. 8 is a likewise enlarged plan view of the improved rotary control valve;

Fig. 9 is a diagrammatic side view of a modified three pocket type of blancher adapted to discharge all of the blanching liquid during each discharge of a treated batch;

Fig. 10 is a diagrammatic top view of a portion of the mechanism of Fig. 9; and

Fig. 11 is a top view of another portion of the assemblage of Figs. 9 and 10.

While the invention has been shown and described herein as being especially applicable for the blanching of relatively small granules such as green peas, the improved method and apparatus are also more generally applicable to the heat treatment of other legumes, berries, vegetables such as beets, and like granular materials. It is not, therefore, desired to unnecessarily restrict the scope or utility of the improvement, to green peas, and this product has merely been cited as one example.

The present improved blancher 21 which is shown in detail in Figs. 1 to 8 inclusive, comprises in general eight independent treating pockets 22 tiltably supported upon a spider 34 secured to a main upright shaft 35 which is journalled for rotation in a main frame 36; an annular series of chutes 23 secured to and revolvable with the shaft 35 above the pockets 22, and each being provided with a lower central downwardly open recess 37 through which an overflow spout 38 on the adjacent pocket 22 is swingable during tilting of the pocket about its horizontal trunnions 39; a variable speed electric motor 40 mounted on the main frame 36 and cooperating with the upper end of the upright shaft 35 through speed reducing gearing 41 so as to slowly revolve the pockets 22 and chutes 23 about the axis of the shaft 35 at any predetermined speed; a series of vertically movable rods or slides 42 reciprocable in guideways 43 carried by the chute supporting spider 44, and each having an actuating roller 45 coacting with cam rails 46 secured to the main frame 36; links 47 connecting the lower ends of the slides 42 with gear segment levers 48 pivotally suspended from the revolving spider 34, the levers 48 having teeth 49 meshing with gears 50 carried by the pocket trunnions 39; a fresh hot liquid chemical measuring and supply unit 26 mounted on the main frame 36 a short distance beyond the fresh legume supply spout 51, and having a rotary control valve

52 operable by projections 53 carried by and removable with the chutes 23, the unit 26 also having a hot liquid discharge pipe 54 directed into the chutes 23; an annular liquid overflow pan or receptacle 55 carried by the revolving spider 34 beneath the outlet ends of the pocket overflow spouts 38 and having a drainage pipe 56 directed downwardly into a stationary annular receptacle 57; a liquid circulating centrifugal pump 58 having a suction pipe 59 communicating with the receptacle 57 and with an expansion tank 60 preferably located so as to avoid overflow of liquid from the receptacle 57, and also having a discharge pipe 61 communicating through a liquid heater 62 with a liquid return pipe 63; and a series of five or more stationary liquid delivery pipes 64 directed into the revolving chutes 23 and each having therein an independent flow control valve 65.

The improved fresh hot chemical supply unit 26 for delivering premeasured batches of hot liquid to the successive revolving pockets 22 through the chutes 23, may be similar in construction to the units shown in my copending application Serial No. 291,159, filed August 21, 1939, and the unit 26 will have a selected capacity corresponding to the size of the pockets 22, and several units 26 may in some cases, be provided. Each of the measuring units 26 comprises a cylinder 66 secured to the stationary frame 36 and having therein a vertically reciprocable floating piston 67 which is movable by fluid pressure acting thereon, between the bottom of the cylinder bore and an adjustable stop 68 as shown in Figs. 4 and 5. A rotary control valve 52 mounted in the base of the cylinder 66 has two arcuate ports 69, 70 therein, and is intermittently rotatable by means of eight radial arms 71 which are engageable by the revolving projections 53 carried by the chutes 23, through successive angles of only forty-five degrees. The fresh liquid supply pipe 25 communicates with one side of the valve chamber, while the measured liquid delivery pipe 54 communicates with the opposite side of the chamber through a goose-neck 72 which rises above the top of the cylinder 66 so as to prevent trapping air. The top of the valve chamber connects with the bottom of the lower piston displacement chamber through a passage 73, while the bottom of the valve chamber communicates with the top of the upper piston displacement chamber through a passage 74; and the stop 68 is vertically adjustable to vary the stroke of the piston 67 and may be retained in adjusted position by means of a set screw 75. When the valve 52 is positioned as shown in Fig. 4, fresh liquid admitted from the supply pipe 25 passes through the valve port 69 and passage 74 into the upper piston displacement chamber, thereby forcing the piston 67 down and delivering the measured batch of liquid from beneath the piston through the passage 73, port 70, goose-neck 72 and pipe 54 to the receiving chute 23 below this pipe. When the valve 52 is revolved forty-five degrees to the position shown in Fig. 8, all ports and passages are sealed; but as the valve 52 is shifted another forty-five degrees to the position shown in Fig. 5, the piston 67 is automatically elevated and the measured batch of liquid above the piston is discharged.

Each of the treating pockets 22 communicates with its overflow spout 38 past a screen 76, as shown in Fig. 2, so that treating liquid may circulate downwardly through the mass of legumes confined within the pocket 22, and may escape

upwardly through the conduit leading to the spout 38, without permitting solids to escape. The spouts 38 serve to establish a definite level of hot treating liquid in each pocket 22, and the liquid which escapes from these spouts 38 drops into the revolving receptacle 55 and escapes therefrom through the pipe 56 into the lower stationary receptacle 57 from whence it is withdrawn by the pump 58 through the pipe 59. The suction pipe 59 should be provided with a drain valve 77 for permitting removal of liquid from the liquid heating and circulating system, and this valve may be placed at the pump 58 or in any other desirable location. The heat exchanger or liquid heater 62 through which the treating liquid passes in flowing from the pump 58 to the distributing pipe 63, may be supplied with regulated quantities of heating medium such as steam through a pipe 78 having a control valve 79 therein, and the spent heating medium may be discharged through a pipe 80. As previously indicated, the distributing pipe 63 communicates with the several final delivery pipes 64 past control valves 65; and by manipulating these valves 65, hot treating liquid can be supplied to any of the pockets 22 at any desired point of travel about the axis of the shaft 35, in order to vary the time of treating or soaking in hot liquid. The temperature of the liquid may obviously be controlled by manipulating the valve 79, thus making the system extremely flexible.

The gearing 41 interposed between the propelling motor 40 and the shaft 35, normally revolves the shaft 35 and the pockets 22 and chutes 23 carried thereby, at a slow rate of speed, and this rate can obviously be varied by varying the motor speed. During the revolution of the pockets 22 from the zone of admission of fresh legumes and liquid to a point just preceding delivery of the batches therefrom, the pockets 22 will travel in upright position and treating liquid may be circulated therethrough by the pump 58, but when the actuating rollers 45 on the successive slides 42 ride down the dip or depression in the fixed cam ring as shown at the right of Fig. 2, the toothed levers 49 and gears 50 become effective to tilt and to invert the corresponding pockets 22 to thereby stop the liquid circulation and dump the treated legumes onto the conveyor 27. Immediately following this dumping, each pocket 22 is again righted preparatory to the reception of a fresh batch or charge.

While the normal operation of the apparatus shown in Figs. 1 to 8 inclusive should be apparent from the foregoing description, a short résumé of this operation will be given. The motor 40 is normally operating to slowly revolve the shaft 35, pockets 22 and chutes 23 at a predetermined speed, and as the successive pockets 22 move past the spout 51 they receive batches of fresh legumes of any selected grade. As the food laden pockets 22 advance past the hot liquid supply unit 26 they are automatically supplied with measured charges of fresh treating liquid. During the advancement of the mixture laden pockets 22 beneath the hot liquid delivery pipes 64, any selected valves 65 of the series, may be opened to admit additional hot liquid to the pockets 22 and to cause a circulation of hot liquid through the pockets 22. For example, if all of the valves 65 are opened, hot liquid will be circulated through each batch of legumes by the pumps 58 throughout the treating period. If only the valve 65 nearest the fresh supply source is opened, hot liquid will only be introduced during the initial

part of the treating period, and the remainder of the period will be devoted to soaking. If none of the initial valves 65 is opened, and hot liquid is admitted only during the end of the treating period, the total treating time may be reduced to a minimum. Therefore, if the operator knows the specific characteristics of the material in the successive batches, he can readily control the machine by manipulating the valves 65 and the heat control valve 79, so as to insure most efficient treatment of each individual batch. The delivery or dumping of the successive heat treated batches at the end of the treating period is accomplished automatically by the cam ring 46 coacting with the rollers 45, and the liquid which is dumped with the treated material, may be wasted, or purified and returned for subsequent use.

In the system of Figs. 1 to 8 inclusive, a certain amount of treating liquid is retained in the heating and circulating portion of the system, and is utilized in the treatment of successive batches of commodity, and this liquid should be periodically removed and replaced. It is possible, however, to utilize my invention in systems wherein the entire treating liquid is completely removed after treatment of each successive batch of material, and such modified system and apparatus is shown diagrammatically in Figs. 9 to 11 inclusive.

The improved modified blancher comprises, a series of any desired number of material confining and treating pockets 22, 22', 22'' each having a screen 76 and an overflow spout 38, and being tiltably supported by trunnions 39 from a spider 34 carried by a revolving upright shaft 35; an annular receptacle 55' carried by and revolving with the spider 34 and being divided by radial partitions 81 into three segregated basins 82, 82', 82'' having drain pipes 83, 83', 83'' respectively disposed at different distances from the axis of the shaft 35; a lower stationary receptacle 57' having therein circular partitions 84 dividing the same into annular basins 85, 85', 85'' which communicate respectively with pump suction pipes 86, 86', 86''; and an automatic drain valve 87, 87', 87'' in each of the pump suction pipes 86, 86', 86'', operable by the pockets 22, 22', 22'' respectively during the dumping movement thereof.

Each of the pipes 86, 86', 86'' forms part of an independent hot liquid circulating system having its own pump 58 and heat transfer device 62 as shown in Fig. 2, and each of the drain valves 87, 87', 87'' is operable by a lever 88 adapted to be actuated by a lug 89, 89', 89'' associated with the bottom of its corresponding pocket 22, 22', 22'' during tilting of the pocket, so as to completely drain the circulating system of each treating pocket when that pocket is dumped. There may be any desired number of treating pockets 22, 22', 22'', and a corresponding number of hot liquid circulating systems, one for each pocket, and the mechanisms for supplying legumes and fresh liquid to the treating pockets, and for revolving and periodically dumping the pockets may be the same as that previously described.

During normal operation of the modified system and apparatus shown in Figs. 9 to 11 inclusive, the pockets 22, 22', 22'' will be revolved slowly about the axis of the shaft 35, and will be supplied with successive batches of legumes and charges of fresh treating liquid from supply units 26 in the manner previously described. Each batch of material may then be blanched or treated

in accordance with requirements, by manipulation of the valves 79, 65 associated with its hot liquid circulating and distributing system; and when the treated batches are discharged by dumping the respective pockets 22, 22', 22'', all of the treating liquid is simultaneously discharged from the corresponding heating and circulating systems, so that each subsequent batch is blanched in nothing but fresh liquid. The overflow from the pocket 22 is delivered to the basin 82 and from thence through the outer pipe 83 into the outer basin 85 from whence it is withdrawn by the pump through the suction pipe 86. The overflow from the pocket 22' is delivered to the basin 82' and from thence through the intermediate pipe 83' into the intermediate basin 85' from whence it is withdrawn by its pump through the suction pipe 86'. Likewise the overflow from the pocket 22'' is delivered to the basin 82'' and from thence through the inner pipe 83'' into the inner basin 85'' from whence it is withdrawn by its own pump through the suction pipe 86''. The drain valves 87, 87', 87'' are operable only by tilting of their respective pockets 22, 22', 22'', and the lugs 88, 88', 88'' are staggered so as to insure such operation. These drain valves are adapted to close automatically after each dumping operation so as to restore the corresponding system to normal operating condition.

From the foregoing detailed description it will be apparent that my present invention provides an extremely flexible and readily manipulable system for most effectively blanching or otherwise heat treating commodities in accordance with their specific requirements. With the improved system, commodities having known characteristics, can be subjected to treatment under controlled temperature, for any desired length or period of time. They can be subjected to temperature increase either slowly or rapidly, and can be permitted to remain under the influence of predetermined temperature, as during soaking, for any desired period of time. While the control valves shown and described herein are manually operable, some of these valves may be operated automatically with the aid of thermostats. However, due to the varying nature of the material, it is perhaps more desirable to utilize manual control. Each successive batch of material can obviously be heat treated so as to insure uniformity in treatment and in quality of the final product, and this may obviously be accomplished with minimum effort and with a minimum number of attendants.

An important feature of my present invention is the internal control of heat by bringing up the treating temperatures either rapidly or slowly, and by circulating the liquid to effect uniform treatment of all of the material, for example, with the improved blancher as shown, the following specific conditions may be effectively fulfilled when the pockets are being revolved at predetermined proper speed:

(a) Each batch of material can be blanched for a definite period of time, of say two minutes only;

(b) Each batch may be brought up to proper temperature in a definite period, of say two minutes, and thereafter permitted to soak for another definite period, of say three minutes;

(c) Each batch of material can be brought up to predetermined temperature in two minutes and thereafter allowed to soak two minutes;

(d) Each batch may be brought up to tem-

perature in two minutes and subsequently soaked one minute;

(e) Each batch can be brought up to temperature in three minutes and permitted to soak one or two minutes;

(f) Each batch may be brought up to temperature in four minutes and allowed to soak one minute; and

(g) Each batch can be brought up to temperature in five minutes, without subsequent soaking.

These examples illustrate the flexibility of the improved system and are purely illustrative of a few of the possible operations. These operations may be effected by regulating the quantity of liquid circulated through the heat exchangers 62 and pockets 22, and the degree of heating of the liquid, and by proper operation of the valves 65. If so desired, each batch of material, may, after initial heating, be permitted to cool slightly, and may be subsequently re-heated, and this may be accomplished by utilizing the cool water supply line 25'. In some cases, such temporary cooling between heating periods is relatively important, and the specific treatment utilized will of course depend largely upon the characteristics of the particular product.

The material is never subjected to human handling, thus maintaining sanitary conditions, and the period of treatment may obviously be prolonged or shortened by varying the speed of revolution of the treating pockets or by proper manipulation of the control valves 65. While the relatively simple system of Figs. 1 to 8 inclusive, does not discard all of the treating liquid after each treatment of a batch, the modified system of Figs. 9 to 11 inclusive will obviously permit such discarding of liquid. Although the improved system is especially useful for blanching peas, it can also be used to advantage in the heat treatment of many other commodities. The improved valve assemblage for the fresh liquid supply unit is operable at slow speed and through limited angles, thereby greatly increasing the life of these valves and reducing the wear to a minimum. These liquid supply units can obviously be utilized in other mechanisms, such as filling machines and other apparatus wherein accuracy in measurement of liquid batches is required.

It should be understood that it is not desired to limit this invention to the exact details of construction or to the precise mode of use, herein shown and described, for various modifications within the scope of the claims may occur to persons skilled in the art.

I claim:

1. A system for blanching comestibles, comprising, means for transporting segregated batches of the material along a definite path, and means for circulating heating medium through each of said batches for a predetermined period of time during advancement thereof.

2. A system for blanching comestibles, comprising, means for segregating the material into relatively small batches and for transporting the batches in succession along a definite path, and means for independently circulating heating medium through each of said advancing batches for a predetermined period of time.

3. A system for blanching comestibles, comprising, means for segregating the material into relatively small batches and for transporting the batches in succession along a definite path, means for independently circulating heating liquid through each of the advancing batches for a

predetermined period of time, and means for automatically removing the heating liquid from each batch.

4. In a blancher, a pocket revolvable about an axis, means for delivering material to said pocket, means for circulating heating liquid through said material while confined within said pocket for a predetermined period of time, means for controllably varying the duration of said circulation, and means for dumping said material from said pocket at a predetermined moment.

5. In a blancher, an upwardly open pocket revolvable about an axis, means for admitting a batch of bulk solids to said pocket, means for circulating heating liquid through said material for a definite period of time, and means for inverting said pocket to dump said solids therefrom at the end of said period.

6. In a blancher, a series of pockets revolvable about an axis, means for admitting batches of bulk solids to the successive pockets of said series, means for controllably circulating heating liquid through each of said pockets for a selected period of time and independently of other pockets of the series, and means for dumping the charges from the successive pockets.

7. In a blancher, a series of pockets revolvable about an axis, means for admitting batches of bulk solids to the successive pockets of said series, means for controllably circulating heating liquid through each of said pockets for a selected period of time and independently of other pockets of the series, and means for inverting the successive pockets to dump the charges therefrom during revolution thereof.

8. In a blancher, an annular series of tilttable receptacles revolvable about an axis, means for admitting a batch of legumes of selected grade to each advancing receptacle, means for independently controllably heating the charge in each of said receptacles, and means for inverting each receptacle to remove the charge therefrom.

9. In a blancher, an annular series of receptacles revolvable about an axis, means for supplying a batch of legumes to each of said receptacles, means for injecting a measured batch of heated liquid into each batch of legumes, means for controllably heating said liquid and for circulating the same through the batch in each receptacle for a predetermined period of time, and means for automatically removing the treated batch from each receptacle.

10. In a blancher, an annular series of receptacles revolvable about an axis, means for sup-

plying a batch of legumes to each of said receptacles, means for injecting a measured batch of heated liquid into each batch of legumes, means for controllably heating said liquid and for circulating the same through the batch in each receptacle for a predetermined period of time, and means for inverting each receptacle after treatment of the material therein to remove the successive batches therefrom.

11. In a blancher, a series of pockets movable about an axis, means for supplying solids to said pockets, means for injecting measured quantities of liquid into said pockets, means for circulating liquid through said pockets for a selected period of time, and means for inverting each of said pockets to dump material therefrom.

12. In a blancher, a series of pockets movable about an axis, means for supplying solids to said pockets, means for injecting measured quantities of liquid into said pockets, means for circulating liquid through said pockets, means for controlling the duration of the period of circulation in each pocket, and means for inverting each of said pockets to dump material therefrom.

13. In a blancher, a series of pockets movable about an axis, means for supplying solids to said pockets, means for injecting measured quantities of liquid into said pockets, means for circulating liquid through said pockets, means for varying the temperature of the liquid circulated through said pockets, and means for inverting each of said pockets to dump material therefrom.

14. In combination, a material confining pocket revolvable about an axis, a measuring device for delivering a predetermined quantity of liquid to said pocket, and a rotary valve operable by the revolution of said pocket to control the delivery of liquid to and from said device, said valve being intermittently rotatable through successive angles less than ninety degrees.

15. In combination, a material confining pocket revolvable about an axis, a measuring device for delivering a predetermined quantity of liquid to said pocket, and a rotary valve movable through successive angles of less than ninety degrees for controlling the flow of liquid to and from said device.

16. A system for blanching comestibles, comprising, means for confining independent batches of material, means for circulating heating liquid through each batch, and means for controlling the temperature of the liquid and the time of circulation to which each batch is subjected.

FRANK D. CHAPMAN.
